Leslie C. Peltier, Delphos, Ohio, assignor to The Delphos
Bending Company, Delphos, Ohio, a corporation of Ohio

Filed May 19, 1960, Ser. No. 60,645

Term of patent 7 years

(Cl. D34—5)

Fig. 1 is a perspective view of a child's rocking toy or similar article, showing my new design;

Fig. 2 is a top plan view thereof; and

Fig. 3 is a front end elevational view thereof.

The essential feature of the present design resides in the contoured outer wall surfaces of the body portion of the child's rocking toy or similar article.

I claim:

The ornamental design for a child's rocking toy or similar article, substantially as shown and described.
